UNITED STATES PATENT OFFICE.

JOSHUA B. HALE, OF PROVIDENCE, RHODE ISLAND, ASSIGNEE, BY MESNE ASSIGNMENTS, TO TEXTILE ENGINEERING COMPANY, A CORPORATION OF RHODE ISLAND.

BRAIDING MACHINE.

Application filed February 5, 1920. Serial No. 356,363.

To all whom it may concern:

Be it known that I, JOSHUA B. HALE, a citizen of the United States, and resident of Providence, in the county of Providence and State of Rhode Island, have invented certain new and useful Improvements in Braiding Machines, of which the following is a specification.

This invention relates to improvements in braiding machines and carriers therefor, and has for its object to provide an improved form of braiding machine in which the quoit members are provided with relatively broad or extended carrier supporting peripheral surfaces, and also to a carrier having a correspondingly extended bearing surface which serves to support it in upright position against its tendency to tip under action of the cop or load above the raceway while traveling rapidly in its zigzag course.

With these and other objects in view, the invention consists of certain novel features of construction, as will be more fully described, and particularly pointed out in the appended claims.

In the accompanying drawings:

Figure 1—is a plan view illustrating a portion of the raceway table with quoit plates rotatably mounted therein.

Figure 2—is a sectional elevation on line 2—2 of Figure 1.

Figure 3—is a side elevation illustrating a pair of quoit members geared together and rotatably mounted on the bed plate of the machine.

Figure 4—is a top view illustrating a portion of the quoit member with a laterally-extending notched driving flange thereon engaging the driving neck portion of the carrier; also illustrating by shaded lines that portion of the flange which serves to enter the space between the divided guiding sections to support the carrier.

Figure 5—is a side elevation showing part of a carrier including that portion which travels and is guided in the raceway.

Figure 6—is a perspective view showing the raceway guiding portion of the carrier partly in section.

It is found in practice in braiding machines where it is required that the carrier should run very rapidly that a very broad or extended bearing surface should be provided on the carrier to support the same in upright position against its tendency to tip

and bind in the raceway due to the centrifugal force and the inertia acting upon the rapidly traveling carrier to throw the load or cop outwardly while traveling in the circular raceway and also in changing its course at the intersections thereof. Then again it is found to be of particular advantage in driving this carrier at a rapid rate of speed that the driving member should engage the carrier centrally or at a point intermediate the upper and lower edges of its guiding or bearing surfaces so as to minimize the tipping effect of the driver upon the carrier.

The following is a detailed description of one form of mechanism which enables me to accomplish the desired results:

Referring to the drawings, 10° designates the bedplate of the machine, which is supported on legs 11. The raceway-table comprises an outer fixed ring 12 and an inner fixed center member 13 in the spaces between which are mounted circular rotatable quoit plates 14. The raceway 15 is formed by providing these quoit plates somewhat smaller in diameter than the openings in the table in which they are set. These quoit plates are preferably circular in shape and each is made in a single unit all mounted on the central hub or pin 16.

The outer or peripheral surface 17 of these quoit plates is relatively broad forming a deep channel or raceway 15 in which the carrier-supporting member, presently described, is set. Midway between the upper and lower edges of this carrier-supporting surface I have provided a narrow annular flange 18 which is provided with a plurality of carrier-receiving notches 19 about its circumference for the purpose presently described.

On the lower edge or to the bottom of this quoit member I have mounted a driving gear 20 which is adapted to mesh with those of the other quoit members to rotate them all in unison.

I have also recessed the upper face of this quoit member as at 21 for the purpose of providing a lubricant-storing chamber having ducts 22 through which the lubricant may pass to oil the surfaces of the different notches 19.

The carrier 23 is provided with an extended body or block having bearing and guiding surface which body or block is divided

at 24 forming an upper bearing surface 25 and a lower bearing surface 26 connected together by a circular driving neck portion 27, which neck portion is adapted to fit into the 5 notches 19 in the flange 18 of the quoit to be driven thereby as the quoit rotates.

By this construction it will be seen that the flange 18 extends into the groove or space 24 between the upper and lower bearing 10 members of the carrier thereby presenting a carrier-supporting surface the extent of which is illustrated by the shade lines at 28 in Figure 4 and as this surface moves with the carrier the driving friction on the latter 15 is reduced to the minimum.

By my improved construction it will be seen that I have obtained a number of important advantages in the operation of a braiding machine; first, the quoit members 20 are made to rotate and are provided with very broad engaging peripheral surfaces which cooperate with a similar supporting surface on the carrier to hold the carrier in an upright position and prevent it from tipping or swaying from side to side as it is moved rapidly through the serpentine race-way; second, I engage the guiding surface of the carrier about midway between its upper and lower guiding members and thus 25 balance the frictional resistance between the upper and lower guiding surfaces due to exerting a driving pressure at a point substantially in the center thereof.

By my improved construction of braiding 30 machine I am enabled to drive the carriers at a very high velocity and by supporting the carriers against an oscillating motion I am enabled to produce a high quality of work which is uniform in character.

40 By the term "broad or extended" as applied to the supporting surface of the quoits and carriers, in both the specification and claims, I wish to be understood as meaning a supporting or bearing face constructed with a substantial distance between its upper and lower bearing edges and the bearing or contacting portion of the surface itself may or may not be continuous between these edges.

50 The foregoing description is directed solely towards the construction illustrated, but I desire it to be understood that I reserve the privilege of resorting to all the mechanical changes to which the device is susceptible, the invention being defined and limited 55 only by the terms of the appended claims.

I claim:

1. In a braiding machine, a plurality of 60 rotatably mounted quoit members adapted to receive a traveling carrier between them and to move the same, each of said quoit members having a broad flange between its upper and lower edges recessed to receive

the stem portion of the carrier, the upper and lower faces of each flange constituting a 65 guiding and bearing surface for engagement with faces of the carriers, and the wall of said quoit members above and below said flange also constituting bearing and supporting surfaces for the carriers. 70

2. In a braiding machine, a plurality of rotatably mounted quoit members adapted to receive a traveling carrier between them and to move the same, each of said quoit members having mating flanges between 75 their upper and lower edges notched to receive stem portions of the carriers, the upper and lower faces of the flanges constituting bearing surfaces for contacting surfaces of the carriers, and the walls of said quoit 80 members both above and below said flanges constituting vertical supports for the carriers.

3. In a braiding machine, a plurality of rotatable quoit members adapted to constitute with the framing of the machine pathways for the carriers and a plurality of traveling carriers having downwardly extending stems with spaced block portions, said quoit members each having between their upper 90 and lower edges broad flanges notched to receive a stem portion of the carriers, and the upper and lower faces of said flanges constituting bearing surfaces for the contacting block portions of the carriers. 95

4. In a braiding machine, a plurality of rotatable quoit members adapted to constitute with the framing of the machine pathways for the carriers and a plurality of traveling carriers having downwardly extending 100 stems with spaced block portions, said quoit members each having between their upper and lower edges broad flanges notched to receive a stem portion of the carriers, and the upper and lower faces of said flanges constituting bearing surfaces for the contacting block portions of the carriers, and the vertical faces of the quoit members above and below said flanges constituting guiding and bearing portions for the vertical faces of said 110 block members.

5. In a braiding machine, a plurality of rotatably mounted quoit members adapted to receive a traveling block-membered carrier between them and to move the same, 115 each of said quoit members having a broad flange, the upper and lower faces whereof are directly engaged by the upper and lower faces of said block members, and the vertical walls of said quoit members above and below said flanges constituting bearing surfaces contacting with the vertical walls of said block portions. 120

In testimony whereof I affix my signature.

JOSHUA B. HALE.
